UNITED STATES PATENT OFFICE.

JAMES F. MC GUIRE, OF NEW YORK, N. Y.

DESIGN FOR A BOTTLE.

SPECIFICATION forming part of Design No. 33,326, dated October 9, 1900.

Application filed August 17, 1900. Serial No. 27,217. Term of patent 14 years.

To all whom it may concern:

Be it known that I, JAMES F. MC GUIRE, a citizen of the United States, residing at New York, borough of Brooklyn, and State of New York, have invented and produced a new and original Design for Bottles, of which the following is a specification, reference being had to the accompanying drawings, forming part thereof, in which—

10 Figure 1 is a side elevation, and Fig. 2 is a plan view, of my design for bottles.

The leading features of my design consist of a neck with straight sides, at the lower portion of which is a bead, a pronounced swell below the bead, and another bead below the swell at the greatest diameter of the bottle, below which lower bead the bottle gradually tapers and then spreads into a base.

15 *a* indicates the neck of the bottle, which is straight and which is terminated by a lip

with an upward and outward curve *b* at its under side. At the lower part of the neck is a double bead *c*, downwardly from which extends a pronounced swell *d*, which is terminated at the greatest diameter of the bottle 25 by another double bead *e*. Below the bead *e* the bottle gradually tapers at *f* and is completed by a base *g*, which spreads out therefrom.

What I claim is—

30 The design for a bottle, substantially as described and shown.

In testimony that I claim the foregoing as my invention I have signed my name in presence of two subscribing witnesses.

JAMES F. MC GUIRE.

Witnesses:

PAUL GOEPEL,
GEO. L. WHEELOCK.
